UNITED STATES PATENT OFFICE.

WILLIAM C. WEFEL, OF DENVER, COLORADO.

ASH-RECEPTACLE.

1,203,289.

Specification of Letters Patent. Patented Oct. 31, 1916.

Application filed July 20, 1915. Serial No. 40,874.

To all whom it may concern:

Be it known that I, WILLIAM C. WEFEL, a citizen of the United States, residing at Denver, in the county of Denver and State 5 of Colorado, have invented certain new and useful Improvements in Ash-Receptacles, of which the following is a specification.

My invention relates to improvements in ash receptacles of the type used in furnace 10 rooms for the temporary storage of ashes, and its primary object is to provide a vessel of this character which is provided with simple and easily operated means for discharging its contents into the opening of an 15 ash pit while closing the same against the escape of ashes exteriorly of the pit.

The ordinary method of emptying the ashes from a receptacle into the opening at the top of the ash pit is usually a source of 20 annoyance, as the slightest wind will blow the ashes away from the opening and frequently onto the body and face of the person performing the operation. By the use of my improved ash receptacle, this annoyance 25 is completely evaded, and the work of emptying the receptacle is at the same time lightened inasmuch as my improved construction permits of the discharge of the contents of the receptacle while it remains 30 in an upright position.

An embodiment of my invention is illustrated in the accompanying drawings in the various views of which like parts are similarly designated and in which,

35 Figure 1 is a side elevation of my improved ash receptacle, Fig. 2, a vertical axial section of the same, and Fig. 3, a transverse section taken along the line 3—3, Fig. 1.

Referring more specifically to the drawings, the reference character 2 designates a receptacle of cylindrical form, provided as usual with handles 3 and a bail 4 and closed at its top by means of a cover 5.

The circumferential wall 6 of the receptacle which is open at its lower end, has 45 interiorly an inwardly flaring flange 7, which constitutes a hopper to direct the contents of the receptacle into an opening over which it is placed.

50 The bottom of the receptacle is composed of a pair of flaps 8 which are hinged for movement about a common axis extending diametrically with relation to its wall. The

flaps which normally close the lower end of the hopper and thereby provide a bottom 55 for the support of the contents of the receptacle, are held in place by a pair of resilient catches 9 secured exteriorly and at opposite points of the inwardly flaring flange. Pull rods 10 connected with the 60 catches, extend through openings in the wall of the receptacle and are provided with knobs 12 to facilitate their outward movement when it is desired to withdraw the catches for the purpose of releasing the 65 flaps. The flaps are provided at their adjoining edges with integral hinge-knuckles which are axially aligned to receive the pintles 13, which are rigidly secured to the flaps by suitable means such as set screws 14 70 shown in Fig. 3. The pintles are extended through openings in the cylindrical wall of the receptacle and their outer portions are bent at right angles exteriorly of the same to provide handles 15 by means of which 75 the flaps may be returned to their normal closing position after the contents of the receptacle have been discharged.

The receptacle may be provided with an external flange as shown at 19 for its support over ash pit openings which in diameter exceed the circumferential surface of the 80 receptacle.

In operation the receptacle is placed in an upright position over the opening in the 85 top of the ash pit thereby separating the same from the surrounding atmosphere. By withdrawing the catches through the medium of the pull rods 10, the flaps forced downwardly by the weight of the contents 90 of the receptacle, are permitted to drop and the ashes are, in consequence, discharged through the hopper 7 into the ash pit without the possibility of their escape exteriorly of the same.

Having thus described my improved ash receptacle in the best form at present known to me, it will be readily understood that modifications in the construction and arrangement of its parts may be resorted to 100 within the spirit of my invention as defined in the following claim.

A portable ash-receptacle including a hollow open-ended body, a bottom normally closing the same at a point between its ends 105 and adapted to open by the weight of matter

supported thereon, a flange on said body adapted to lap over an edge of an opening in which the lower portion of the body is inserted, means for holding said bottom in 5 its normal position, and means for releasing the same at a point exteriorly of the body and above its said flange.

In testimony whereof I have affixed my signature in presence of two witnesses.

WILLIAM C. WEFEL.

Witnesses:

G. J. ROLLANDET,
M. C. BRADLEY.
